UNITED STATES PATENT OFFICE

149,798

DESIGN FOR A CHAIR

Richard W. Crawford, Flint, Mich.

Application January 20, 1947, Serial No. 136,252

Term of patent 3½ years

(Cl. D15—1)

To all whom it may concern:

Be it known that I, Richard W. Crawford, a citizen of the United States, residing at Flint, in the county of Genesee and State of Michigan, have invented a new, original, and ornamental Design for a Chair, of which the following is a specification, reference being had to the accompanying drawing, forming part thereof.

Figure 1 is a rear perspective view of a chair, showing my new design.

Figure 2 is a cross sectional view taken substantially in the plane of the line 2—2 of Figure 1, and

Figure 3 is a front perspective view of the chair shown in Figure 1, on a reduced scale.

I claim:

The ornamental design for a chair, as shown.
RICHARD W. CRAWFORD.
